UNITED STATES PATENT OFFICE.

EDMUND DEYETTE, OF SAN FRANCISCO, CALIFORNIA.

DESIGN FOR A DIRECTION SIGNAL.

Application filed July 22, 1922. Serial No. 3,175. Term of patent 3½ years.

To all whom it may concern:

Be it known that I, EDMUND DEYETTE, a citizen of the United States, residing at 409 Laguna St., in the city of San Francisco, county of San Francisco, and State of California, have invented a new, original, and ornamental Design for a Direction Signal, of which the following is a specification, reference being had to the accompanying drawing, forming part thereof.

Fig. 1 is a perspective view of a direction signal showing my new design and Fig. 2 is a top plan view thereof.

I claim:

The ornamental design for a direction signal, as shown.

EDMUND DEYETTE.
